FIG. 6

SELF-SHIELDING TYPE CYCLOTRON

This invention relates to an improvement in or relating to a cyclotron, and more particularly to a self-shielding type cyclotron which makes it unnecessary to enclose the cyclotron by an extra shielding structure to protect personnel or equipment from radiation injury or damage.

Referring to FIGS. 1 and 2, there is shown a conventional cyclotron in which a vacuum casing 3 contains two accelerating electrodes (called "dees") 2, and is disposed between the poles 1 of a magnet structure. Also, as shown in the drawings, in the opening defined by the opposite yokes 9 of the magnet structure there are together disposed a high-frequency power inlet 4 to the dees, an exhaust 6 to a vacuum pump 5 and an outlet 8 for extracting ions. The ions are accelerated and deflected by a deflector 7. Thus, the opening defined by the magnet yokes 9 will leak radiation while the cyclotron is running, and therefore it is necessary that an extra shield structure to surround the cyclotron be provided to protect personnel or equipment from radiation injury or damage. In this connection, the floor space required for installation of the cyclotron is as large as the floor space of the cyclotron per se plus that of the shielding structure. Therefore, in installing a cyclotron, extra space and cost is inevitable. Recently a different type cyclotron has been proposed, in which a high-frequency electric power is supplied to the dees via a coaxial unit mounted at the center of the magnet pole. A cyclotron of this type has a resonator, an exhaust, an ion outlet and other accessories disposed in the opening of the magnet structure, and therefore it also necessitates a radiation-shielding structure.

The object of this invention is to provide a self-shielding type cyclotron which is compact and less expensive, and facilitates installation thereof.

Other objects and advantages of this invention will be apparent from the following description which is made with reference to the accompanying drawings in which:

FIG. 1 is a plan view of a conventional cyclotron, partially broken;

FIG. 2 is a side view of the conventional cyclotron as shown in FIG. 1;

FIG. 3 is a vertical section of a cyclotron according to this invention;

FIG. 4 is a cross section of the cyclotron, taken along the line o—o' in FIG. 3; and

FIGS. 5 and 6 are similar to FIGS. 3 and 4, but showing another embodiment of this invention.

Referring to FIGS. 3 and 4, a cyclotron according to this invention comprises a pair of annular bodies A, A', integrally assembled in the over laying relation. An annular body has a center leg portion 11 (hereinafter referred to as "pole") and a peripheral leg 10 (hereinafter referred to as "yoke"), thus taking a form of the letter "E" in vertical section. In the drawings, 13 is an electromagnet coil (called "Bitter" type electromagnet); 15 dees positioned in the first space 14 defined by the opposite poles 11; 17 a target box mounted in the second space 16 defined by the opposite magnet coils 13; 19 coaxial elements of the resonator disposed in the central apertures 18 of the poles and connected to the dees; and 20 a wall for keeping the first space 14 vacuum-tight. 21 is a short-circuit plate of the coaxial elements; 22 a beam deflector; 23 is an ion source 24 a vacuum-tight gasket; 25 linear shafts which allow a hy-

draulic jack (not shown) to raise the upper annular body A; and finally 26 an exhaust duct to the vacuum pump (not shown).

As shown in these drawings a cyclotron is consisted of a pair of annular counterparts integrally connected in a vacuum-tight fashion. Within this vacuum-tight assembly there are disposed a vacuum box, a target box and other accessories. Thanks to this unique structure, and if the wall of the yoke 10 has a thickness enough to prevent radiation from passing through the yoke, little or no radiation will appear outside of the cyclotron.

Two coaxial elements 19 of the resonator are inserted in the center apertures 18 of the opposite poles 11. This center aperture extends over a relatively long distance, compared with the diameter of the aperture. Therefore, it will leak no appreciable amount of radiation. As to the exhaust 26 to the vacuum pump, it extends through the yoke 10 in the form of labyrinth, and therefore it will not leak an appreciable amount of radiation, either. The lead wires to the coils of the electromagnets 13 and the gas supply pipes to the ion source are put in the apertures of such a small diameter that they may leak a negligible small amount of radiation.

In this particular embodiment a split type dee is used, and therefore when putting the upper annular body A on the lower one A', one counterpart of the dee mounted in the upper annular body A must accurately mate with the other counterpart of the dee housed in the lower annular body A'. Any misalignment of these counterparts will cause unstable operation in the resonator.

Now, the shielding capability of a cyclotron according to this invention will be discussed, taking the operating condition of 4 MeV, 10 μ A deuteron as an example. γ -ray and neutron will be generated when deuteron is accelerated in the cyclotron. However, if the shielding against neutron is satisfied, then the shielding against γ -ray will suffice. In this connection the shielding capability against neutron is handled in the following. In the event of bombardment against a Be target by the deuteron as specified above, a large number of neutrons will be produced, and for the operating condition above mentioned the number of neutrons thus generated is:

$$\frac{10 \times 10^{-6}}{1.6 \times 10^{-19}} \times \frac{8}{10^4} = 5 \times 10^{10}/\text{sec.}$$

At a one meter distance from the Be target the amount of radiation is $4 \times 10^5/\text{cm}^2 \cdot \text{sec}$. As is well known, the dose of neutrons (in terms of "rem") depends on the energy of neutron, 1-mr is equal to about $10^6/\text{cm}^2$ for thermal neutrons, and is equal to about $10^5/\text{cm}^2$ for 100 KeV fast neutrons. For the approximate estimation thermal neutron is 80 percent of the total number of neutrons, and 100 KeV fast neutron is 20 percent. Therefore the dose rate of thermal and fast neutrons is 1.1 mr/sec. In case of targets other than the Be target, such as CO_2 , N_2 or H_2O target, the rate of generation of neutrons is approximately one tenth of that in case of the Be target, i.e., about 0.1 mr/sec.

Suppose that the cyclotron is running for 30 hours per week. In case of the Be target the neutrons will be about 1×10^5 mr/week, whereas in case of targets other than the Be target the neutrons will be about 1×10^4 mr/week. The allowable dose at the boundary of the controlled area is 30 mr/week.

65

Suppose that the yoke of the assembly is made of an iron as thick as 30 cm. Most neutrons take an oblique path in passing through the yoke wall, and therefore effective thickness of the yoke wall is as large as about 45 cm. As is well known, an iron sheet as thick as 15 cm will reduce the neutron flux 10 times. Therefore, a 45 cm-thick iron sheet will reduce the neutron flux 1,000 times.

As for the above examples, in case of the Be target the radiation dose at a 1 m-distance will be 100 mr/week, whereas in case of targets other than the Be target the radiation dose will be 10 mr/week.

In case of the Be target the radiation dose is three times as large as the allowable value, and therefore the controlled area must extend and cover 2 meters around the cyclotron.

Alternatively, the cyclotron may be applied by a paraffin coating several centimeters thick. In case of targets other than the Be target, however, the radiation dose is one third of the allowable value, causing no radiation injury or damage.

Referring to FIGS. 5 and 6, there are shown another embodiment of this invention. This cyclotron is structurally the same as the first embodiment of FIGS. 3 and 4 except for; the coaxial elements 19 of the resonator system extend through the yoke 10 of the annular assembly to the dees 15, and the second space 16 is partially loaded with a shielding material 27 (such as paraffin or boron-and-paraffin mixture coated with a cadmium plate) around each coaxial unit.

This structure is advantageous to the integral connection between the dees 15 and the coaxial element 19, assuring a sufficient mechanical strength in the joint. Also, this arrangement permits the use of an integral type resonator in place of the split type-one, thus avoiding the unstable operation which would be caused by any misalignment of respective counterparts of the split type resonator when assembled.

The leak of the radiation from a target box can be prevented by putting a 30 cm-thick, cadmium-coated paraffin or paraffin-and-boron mixture layer on the coaxial element of the resonator in the second space. These particular shielding materials as thick as 20 cm will decrease neutron flux 10 times. Suppose that on an average neutrons pass through the shield obliquely at 30°, and therefore the apparent and effective thickness is as large as 36 cm. Thus, the neutron flux will decrease 60 times. Suppose that the coaxial element of the resonator is, for instance, 15 cm in diameter and 45 cm in length. The neutrons when passing through this cylindrical duct are supposed to decrease about 30

times. As a total result the neutron flux will decrease 1,800 ($1/60 \times 1/30 = 1/1800$). This figure proves the satisfactory self-shielding attained in a cyclotron according to this invention.

As mentioned earlier, a cyclotron according to this invention is a closed structure, contrary to the conventional open-type cyclotron. Usually a 30 cm-thick yoke is adequate to prevent the leak of radiation. The thickness of the yoke increases with the energy of the cyclotron in designing.

The unique structure of this invention is advantageous particularly to a small-sized cyclotron having a target material other than Be (such as B, C, N, O, Ne and other elements) for use in producing short-life radioisotopes for medical use, or in generating neutrons or charged particles for radiochemical analysis.

What is claimed is:

1. A cyclotron comprising: a pair of annular counterpart bodies overlying and integrally assembled with each other, each said annular counterpart body having, in section, a center leg comprising a pole and two side legs comprising a yoke in the form of the letter "E", said yoke having a thickness adequate to prevent radiation from passing therethrough; electromagnet coils positioned around said pole and surrounded by said yoke; dees positioned in the first closed space defined by the opposite end surfaces of said pole; a target box positioned in the second space defined by the opposite surfaces of said electromagnet coils; a resonator comprising co-axial means inserted axially in central apertures of said poles and integrally connected to said dees; and gas-tight means for keeping vacuum at least in said first closed space.

2. A cyclotron comprising: a pair of annular counterpart bodies overlying and integrally assembled with each other, each said annular counterpart body having, in section, a center leg comprising a pole and two side legs comprising a yoke in the form of the letter "E", said yoke having a thickness adequate to prevent radiation from passing therethrough; electromagnet coils positioned around said pole and surrounded by said yoke; dees positioned in the first closed space defined by the opposite end surfaces of said pole; a target box positioned in the second space defined by the opposite surfaces of said electromagnet coils, a resonator comprising co-axial means extending transversely through said yokes and integrally connected to said dees; radiation shield means positioned around said co-axial means in said second space; and gas-tight means for keeping vacuum at least in said first closed space.
